ENCLOSURE FOR RECORDER

James Teague, Glenview, Ill., assignor to Texas Instruments Incorporated, Dallas, Tex., a corporation of Delaware

Application June 29, 1956, Serial No. 42,097

Term of patent 14 years

(Cl. D26—14)

FIG. 1

FIG. 2

FIG. 3

The essential features of my design reside in the portions shown in solid lines on the drawings.

Portions of the drawings of Figures 1, 2 and 3 are diagonally lined to indicate transparency.

I claim:

The ornamental design for an enclosure for recorder, substantially as shown and described.
